225,306

HINGE FOR CABINETS OR THE LIKE

James L. Pruitt, Bellevue, Nebr.
(P.O. Box 262, Strawn, Tex. 76475)

Filed June 18, 1970, Ser. No. 23,563

Term of patent 14 years

Int. Cl. D8—06

U.S. Cl. D8—189

FIG. 1

FIG. 3

FIG. 2

FIG. 4

FIG. 1 is a top plan view of my new design for hinge for cabinets or the like, the bottom plan view being a substantial mirror image thereof;

FIG. 2 is a rearward elevational view of said hinge;

FIG. 3 is a leftward end view, the rightward end elevational view being a substantial mirror image thereof; and

FIG. 4 is a forward elevational view of my new design for hinge for cabinets or the like.

I claim:

The ornamental design for hinge for cabinets or the like, as shown and described.
